(57) **CLAIM**

The ornamental design for an insulin pump, as shown and described.

DESCRIPTION

FIG. 1 is a top view of the insulin pump comprising a new, original and ornamental design;

FIG. 2 is a rear view of the insulin pump comprising the new, original and ornamental design;

FIG. 3 is a bottom view of the insulin pump comprising the new, original and ornamental design;

FIG. 4 is top, rear exploded perspective view of the insulin pump comprising the new, original and ornamental design;

FIG. 5 is a front view of the insulin pump the new, original and ornamental design;

FIG. 6 is a top, front perspective view of the insulin pump comprising the new, original and ornamental design; and,

FIG. 7 is a left-hand side view of the insulin pump comprising the new, original and ornamental design.

The broken lines illustrate environmental structure of the insulin pump, which forms no part of the claimed design.
